(57) **CLAIM**

The ornamental design for a mixed reality system, as shown and described.

DESCRIPTION

FIG. 1 is a perspective view of the mixed reality system, as seen from the front, left side;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a perspective view thereof showing the location of a head strap, pack straps, and connecting cabling; and, FIG. 9 is a left-side view thereof showing the mixed reality system worn by a user.

The broken lines in FIGS. 3, 8 and 9 depict portions of the article or are included for the purpose of illustrating an in-use configuration of the article and form no part of the claimed design.
